UNITED STATES PATENT OFFICE.

EDWARD D. MACKINTOSH, OF BROOKLYN, ASSIGNOR TO PAUL PRYIBIL, OF NEW YORK, N. Y.

SWING-SAW MACHINE.

SPECIFICATION forming part of Letters Patent No. 396,218, dated January 15, 1889.

Application filed April 18, 1888. Serial No. 271,046. (No model.)

To all whom it may concern:

Be it known that I, EDWARD D. MACKINTOSH, of Brooklyn, in the county of Kings and State of New York, have invented a new and useful Improvement in Swing-Saw Machines, of which the following is a specification.

This invention relates to swing-saw machines in which the saw is made to cut in a straight line or such other line as may be desired by means of a guide-rail which supports the swinging frame and controls its swinging movement, as described in Patent No. 370,962, dated October 4, 1887. In such machine, as in all swing-saw machines, some provision is desirable for raising and lowering the swinging frame and the saw to make the saw travel on a higher or lower level. In the machine described in the aforesaid patent this raising or lowering of the frame is effected by raising or lowering the frame relatively to the guide-rail, the latter remaining stationary or at a fixed level. This method of adjustment involves a deviation from the normal line of movement of the saw-shaft produced by the swinging movement of the frame.

The object of my invention is to provide for the raising and lowering of the frame and saw without any departure of the saw-shaft from the normal line of movement, except the rising and falling of said line; and to this end I provide for the adjustment of the guide-rail and the swinging frame together without the necessity of any change in their relation to each other; and my invention consists in a combination, hereinafter described and claimed, for such an adjustment.

This invention also consists in the combination, as hereinafter described and claimed, with a swinging saw-frame and a guide-rail for controlling the swinging movement of the same, of a spring for the purpose of counterbalancing or sustaining the weight of the said saw-frame.

In the accompanying drawings, Figure 1 is a side view of a swing-saw machine embodying my invention. Fig. 2 is a front view of the same, and Fig. 3 is a horizontal sectional view showing the adjustable guide-rail and its fixed support and means of adjustment.

Similar letters of reference designate corresponding parts in the several figures.

S S designate fixed uprights, constituting the stationary framing of the machine.

A designates the swinging saw-frame, and B the driving-shaft upon which it swings.

D D are the fixed upright brackets, which constitute or contain the bearings in which the frame A swings, and in which the said frame and the shaft B are capable of a vertical movement.

C designates the saw-shaft, arranged in bearings in the lower part of the swinging frame A and carrying the saw C' or any rotary cutter.

B' is a pulley on the driving-shaft B, from which a belt, b, runs to a pulley, C², on the shaft C, for the purpose of driving the saw or rotary cutter.

E designates the guide-rail, attached to one of the uprights S, and F is a roller attached to one side of the frame A and running on the said guide-rail. The guide-rail, instead of being secured directly to the post S, is made to form part of a bracket, E', which is fitted to slide on an upright dovetailed plate, G, firmly secured to the said post, and is capable of adjustment upward and downward on said plate by means of a screw, H, which is fitted to turn freely but confined longitudinally in a bearing in a lug, d, provided on the lower part of said plate, and which screws through a female screw in a lug, e, provided on the lower part of the guide-rail or bracket E'.

By turning the screw H by hand the bracket and the guide-rail may be moved upward and downward, and, as the rail supports the swinging frame and the shafts B and C, the frame and the saw are raised and lowered with the guide-rail without any change in their relation, and in the swinging movement of the frame the shaft C is caused to describe the same line without regard to the height of the guide-rail or the distance of the said shaft from the saw-table.

I designates a spiral spring, one end of which is connected with the swinging frame A, and the other end of which is connected with the guide-rail at f. This spring tends to draw the swinging frame to an upright position and to counterbalance in some degree the weight of said frame and its contents, and, being connected with the guide-rail, is adjustable there-

with, along with the said rail, the swinging frame, and the shaft C and saw or cutter C', so that its pull on the saw-frame is not varied by the adjustment of the guide-rail. The said spring, which is a tension-spring acting by a pulling action, becomes more powerful as the frame moves from a vertical position, and the force required to counterbalance it is greater.

What I claim as my invention, and desire to secure by Letters Patent, is—

1. The combination, with the swinging and bodily rising and falling frame, the driving-shaft about which said frame swings, and the shaft for the saws or rotary cutter carried by said frame, of a guide-rail for supporting said frame and guiding it in its swinging move-

ment, a fixed support for said guide-rail, and means of adjusting said guide-rail on said support, all substantially as herein described, whereby the frame and shafts are all adjusted 20 with said guide-rail, as herein set forth.

2. The combination of the swinging saw-frame, the adjustable guide-rail E, and the spring I, connecting the said frame with the said rail and adjustable along with said rail 25 and frame, substantially as herein described, and for the purpose set forth.

EDWARD D. MACKINTOSH.
